Primary Examiner — Thomas Johannes(74) *Attorney, Agent, or Firm* — Kenneth M. Bush; Bush Intellectual Property Law(57) **CLAIM**

I claim the ornamental design for a strike plate for fuse cutout assembly, as shown and described.

DESCRIPTION

FIG. 1 is a right side, top, rear perspective view of a strike plate for fuse cutout assembly showing my new design;
FIG. 2 is a left side, bottom, front perspective view thereof;
FIG. 3 is a right side elevation view thereof;
FIG. 4 is a left side elevation view thereof;
FIG. 5 is a top plan view thereof;
FIG. 6 is a bottom plan view thereof;
FIG. 7 is a rear elevation view thereof; and,
FIG. 8 is a front elevation view thereof.
